ELECTRIC FUSE

Edward V. Sundt, Wilmette, Ill., assignor to Sundt Engineering Company, Des Plaines, Ill., a corporation of Illinois

Application May 18, 1953, Serial No. 355,542

14 Claims. (Cl. 200—121)

This invention relates to electric fuses for protecting electric circuits from overload conditions.

The principal object of this invention is to provide an improved fuse which embodies a new principle of construction and operation, which provides new and improved results, which prevents the establishment of a sustained arc, which prevents the building up of excessive pressures in the fuse, which protects against high overloads even of small duration, which may protect against low overloads over periods of time, which quickly visually indicates the conditions of the fuse, and which may be inexpensively manufactured.

Briefly, the electric fuse of this invention includes a thin sheet conductor of fuse metal, and a rod shaped conductor having its end engaging and preferably secured to one side of the thin sheet conductor at a point within the area of the thin sheet conductor. Preferably, the transverse dimensions of the point of engagement of the conductors is greater than the thickness of the thin sheet conductor and the cross sectional conductive area of the thin sheet conductor immediately about the point of engagement is less than any other cross sectional conductive area of the thin sheet conductor. The conductors are connected in series with the electric circuit to be protected so that, upon a predetermined overload in the electric circuit, fusion takes place in the area of the thin sheet conductor about the point of engagement of the conductors and provides an ever widening gap between the conductors. This results in the arc, after striking, being unable to establish itself in one place long enough to cause damage. The establishment of sustained arcs is therefore prevented and the arc is quickly extinguished. Building up of excessive or dangerous pressures in the fuse upon the blowing of the fuse, is also prevented by reason of the quick extinguishment of the arc.

The thin sheet conductor of the fuse may be provided with indicia, such as for example "O. K.", for indicating the condition of the fuse, these indicia being located on the opposite side of the thin sheet conductor adjacent the point of engagement of the conductors. When the thin sheet conductor fuses, upon blowing of the fuse, the indicia are at the same time obliterated. The indicia are readily visible through a transparent window in the fuse for checking the condition of the fuse.

In the operation of the electric fuse of this invention, the fuse blows on high overloads because the high current density, in the area of the thin sheet conductor around the point of engagement of the conductors, heats up the thin sheet conductor to its fusion temperature for instantly melting the same on high overloads, as for example, above 500% of the fuse rating, which would be caused by shorting or the like. The fuse also blows under another condition, a sustained low overload condition. Here, the point engagement of the conductors heats up to the fusion temperature of the thin sheet conductor by reason of current passage, and is so designed to be a factor in sustained overloads which may be only 125% of the fuse rating.

In order to prolong the time interval required to blow the fuse on low overload conditions, the rod shaped con-

2

ductor may be made tubular at its end adjacent the point where it engages the thin sheet conductor and filled with a fuse metal which is of lower melting point than that of the thin sheet conductor. The fuse metal, preferably a eutectic alloy, absorbs considerable heat before it changes from solid to liquid at the fusion temperature thereof. This fuse metal, in intimate contact with the rod shaped conductor, causes the temperature of the rod shaped conductor to follow substantially that of the fuse metal. As a result, additional lag or time delay is obtained in raising the temperature of the point of engagement of the conductors to the value necessary to fuse the thin sheet conductor. This is true for two reasons: one, heat, and therefore watts, are required to bring the temperature of the rod shaped conductor up to melting point of its fuse metal because of its specific heat, and two, on reaching this temperature no further rise in temperature takes place until this fuse metal is melted because of the latent heat of fusion thereof. In this way, long time delays may be obtained which are useful in circuits having motors, solenoids, magnets and other equipment having high starting currents.

The electric fuse of this invention may be embodied in any desired type of fuse, such as for example, a plug type fuse or a cartridge type fuse. In the case of the former, the conductors of the fuse are electrically connected to the usual metal screw shell and the metal contact rivet and the indicia is located adjacent the transparent window in the end of the plug body. In the case of the latter, the conductors are electrically connected to the usual metal fuse caps. The condition of the fuse may be seen through the tubular wall of the fuse body which may be made of transparent material.

Further objects of this invention reside in the details of construction of the electric fuse and in the cooperative relationships between the component parts thereof.

Other objects and advantages of this invention will become apparent to those skilled in the art upon reference to the accompanying specification, claims and drawings in which:

Figure 1 is a perspective view of one form of the electric fuse of this invention.

Figure 2 is a top plan view of the electric fuse illustrated in Figure 1 but showing the condition of the fuse after the same has blown.

Figure 3 is a vertical sectional view taken substantially along the line 3—3 of Figure 2 but illustrating the fuse in operative condition.

Figure 4 is a view similar to Figure 3 but showing another form of the electric fuse of this invention.

Figure 5 is a vertical sectional view through still another form of the electric fuse of this invention.

Figure 6 is a sectional view taken substantially along the line 6—6 of Figure 4.

Referring first to Figures 1 to 3 one form of the electric fuse of this invention is generally designated at 10, it being a plug type electric fuse. The electric fuse includes a hollow plug member 11 made of suitable insulating material such as Bakelite or ceramic and which is provided with an end wall. A metal screw shell 12 is suitably secured to the exterior of the plug member 11 and forms one of the electrical connectors for the fuse. A metal contact rivet 13 is secured to and extends through the end wall of the plug member 11 and forms the other electrical connection of the fuse. A thin sheet conductor 14 formed of suitable fuse material and having a substantial planar dimension and a thickness sufficient to be self-supporting is located within the fuse member and has an extension 15 which extends through an opening 16 in the plug member and is secured as by soldering or welding to the metal screw shell 12 as indicated at 17.

A rod shaped conductor 18 of relatively small transverse dimension is formed on the metal contact rivet 13 and is arranged normal to the thin sheet conductor 14. The end of this rod shaped conductor 18 engages the under side of the thin sheet conductor 14 at a point 20 within the planar area of the thin sheet conductor. Preferably the rod shaped conductor 18 is secured to the thin sheet conductor 14 by welding or the like to assure good electrical contact, the welding being accomplished by condenser welding. Thus, an electric circuit is established through the electric fuse from the metal screw shell 12 through the thin sheet conductor 14 and the rod shaped conductor 18 to the metal contact rivet 13 and in this way the electric fuse may be incorporated in an electric circuit for protecting the same.

The transverse dimensions of the rod shaped conductor 18 and, hence, the point of engagement 20 of the conductors 18 and 14 are greater than the thickness of the thin sheet conductor 14. For example, the transverse dimension or diameter of the rod shaped conductor 18 and, hence, the point of engagement 20 of the conductors may range from .010 to .060 inch while the thickness of the thin sheet conductor 14 may range from .003 to .010 inch, these dimensions depending on the fuse rating. The cross sectional conductive area of the thin sheet conductor immediately about the engaging or securing point 20 is less than any other cross sectional conductive area of the thin sheet conductor. These dimensions are particularly applicable in connection with fuses of 30 amperes or less where the thin sheet conductor 14 is made of an alloy such as 98.5% zinc and 1.5% copper.

The open end of the plug member 11 may be closed by a transparent window 21 which may be held in place on the plug member by means of a suitable ring 22. The upper side of the thin sheet conductors 14 adjacent the point of engagement 20 may be provided with suitable indicia such as "O. K." as indicated at 23 in Figure 1 and this indicia is readily visible through the transparent window 21.

The electric fuse 10 is adapted to protect electric circuits against two types of overloads in the circuit, namely, a high overload such as caused by shorting of the circuit and a low overload persisting over a predetermined interval of time.

When a high overload occurs in the circuit, as for example, an overload of 500% of the rating of the fuse, a heavy current flow instantly passes through the fuse and as a result there is a high current density in the thin sheet conductor 14 immediately adjacent the point of engagement 20. This high current density instantly melts the thin sheet conductor at this point for the purpose of breaking the circuit. When fusion at this point takes place, an ever widening gap between the point of engagement 20 and the remainder of the thin sheet conductor 14 is brought about. This in turn results in the arc, after striking, being unable to establish itself in one place long enough to cause damage. In other words, it is as if the arc had an infinite number of places at which it can strike in the area surrounding the point of engagement 20. The result is that the arc is quickly extinguished and the establishment of sustained arcs is effectively prevented. When the thin sheet conductor 14 is so fused, as indicated at 24 in Figure 2, the indicia 23 is at the same time obliterated so that when the fuse is blown by an overload condition, this is readily discernible through the transparent window 21.

If a low overload condition persists in the circuit being protected for a relatively long period of time, as for example, an overload of 125% of the rating of the fuse, the increased current flow heats the rod shaped conductor 18 and the point of engagement 20. Following an interval of time, required to heat the point of engagement 20 up to the fusion temperature of the thin sheet conductor 14, the thin sheet conductor 14 then rapidly melts at this point for the purpose of breaking the circuit. Here also,

an ever widening gap between the point of engagement 20 and the remainder of the thin sheet conductor takes place with the resultant beneficial results described above. Delayed melting of the thin sheet conductor 14 on low overload conditions is afforded by the time required to raise the temperature of the rod shaped conductor 18 and, hence, the point of engagement 20 up to the fusion temperature of the thin sheet conductor 14. Conversely, immediate melting of the thin sheet conductor 14 on high overload conditions is brought about by reason of the fact that the thickness of the thin sheet conductor 14 is considerably less than the transverse dimensions of the rod shaped conductor 18 so that the current density in the thin sheet conductor 14 is considerably greater than that in the rod shaped conductor 18.

Figure 4 illustrates another form of the invention wherein provision is made for increasing the elapsed time required for blowing the fuse on sustained low overload conditions. With one exception the fuse of Figure 4 is 20 like that shown in Figures 1 to 3 and it operates in the same manner and accordingly like reference characters have been utilized for like parts. In Figure 4, the rod shaped conductor 18 has been hollowed out or made tubular and is filled with a fuse metal 19 which is of lower 25 melting point than that of the thin sheet conductor 14. This fuse metal 19 may be a eutectic alloy, such as 63% tin and 37% lead, and absorbs considerable heat before it changes from solid to liquid at its fusion temperature. This fuse metal 19, which is in intimate contact with the rod shaped conductor 18, causes the temperature of the rod shaped conductor 18 to follow substantially the temperature of the fuse metal 19. In this way the temperature of the rod shaped conductor 18 is held down to the liquefying temperature of the fuse metal 19 until it is 30 fully melted. In other words, increased lag or time delay is here brought about because of two factors, one, heat, and therefore watts, are required to bring the temperature up to the melting point of the fuse metal because of its specific heat, and two, on reaching the temperature no further rise in temperature takes place until the fuse metal is melted due to the latent heat of fusion thereof. In this way long time delays may be obtained which are 35 useful in circuits having motors, solenoids, magnets and other equipment having high starting currents and yet 40 the electric circuit is protected against low overloads existing over long periods of time.

The electric fuse generally designated at 26 in Figures 5 and 6 is a cartridge type fuse which is somewhat different in construction, but which operates in the same 45 manner as the plug type fuse 10 illustrated in Figures 1 to 4. In Figures 5 and 6 the cartridge type fuse 26 includes a tube member 27 formed of suitable insulating material such as ceramic, glass or the like and preferably it is made transparent so that the condition of the fuse 50 may be visually determined. The ends of the tubular member 27 are closed by conventional metal fuse caps 28 and 29. A thin sheet conductor 30 is located within the tubular member 27 and is provided with an extension 31 which is electrically connected to the fuse cap 55 29. A rod shaped conductor 32 is located within the tubular member 27 and is carried and electrically connected by a member 33 secured to the other fuse cap 28. The end of the rod shaped conductor 32 engages one 60 side of the thin sheet conductor 30 at a point 34 within the area of the thin sheet conductor and preferably the conductors are secured together as by condenser welding or the like. The manner of operation of the cartridge type fuse 26 is the same as that described above 65 in connection with the plug type fuse 10 and, therefore, a further description is not considered necessary. Here, the condition of the fuse is visually determined through the transparent tubular member 27 and the thin sheet conductor 30 may be provided with indicia similar to the indicia 23 of the electric fuse 10. Here, also, the rod shaped conductor 32 may or may not be provided with 70 75

a low melting point fuse metal depending upon whether or not prolonged low overload protection is desired.

While for purposes of illustration several forms of this invention have been disclosed other forms thereof may become apparent to those skilled in the art upon reference to this disclosure and, therefore, this invention is to be limited only by the scope of the appended claims.

I claim as my invention:

1. An electric fuse comprising a thin sheet conductor of fuse metal, a rod shaped conductor having fuse metal of lower melting point than that of the thin sheet conductor and having its end engaging one side of the thin sheet conductor at a point within the area of the thin sheet conductor, and means for connecting the conductors in series in an electric circuit so that, upon a predetermined high overload in the electric circuit which may be of short duration, or upon a predetermined low overload existing for an extended interval of time, fusion takes place promptly in the area of the thin sheet conductor about the point to provide an ever widening gap between the conductors.

2. An electric fuse comprising a thin sheet conductor of fuse metal, a rod shaped conductor having a fusible eutectic alloy of lower melting point than that of the thin sheet conductor and having its end engaging one side of the thin sheet conductor at a point within the area of the thin sheet conductor, and means for connecting the conductors in series in an electric circuit so that, upon a predetermined high overload in the electric circuit which may be of short duration, or upon a predetermined low overload existing for an extended interval of time, fusion takes place promptly in the area of the thin sheet conductor about the point to provide an ever widening gap between the conductors.

3. An electric fuse comprising a thin sheet conductor of fuse metal, a rod shaped conductor having fuse metal of lower melting point than that of the thin sheet conductor and having its end engaging one side of the thin sheet conductor at a point within the area of the thin sheet conductor, the transverse dimensions of the point of engagement of the conductors being greater than the thickness of the thin sheet conductor, and means for connecting the conductors in series in an electric circuit so that, upon a predetermined high overload in the electric circuit which may be of short duration or upon a predetermined low overload existing for an extended interval of time, fusion takes place promptly in the area of the thin sheet conductor about the point to provide an ever widening gap between the conductors.

4. An electric fuse comprising a thin sheet conductor of fuse metal, a rod shaped conductor having a fusible eutectic alloy of lower melting point than that of the thin sheet conductor and having its end engaging one side of the thin sheet conductor at a point within the area of the thin sheet conductor, the transverse dimensions of the point of engagement of the conductors being greater than the thickness of the thin sheet conductor, and means for connecting the conductors in series in an electric circuit so that, upon a predetermined high overload in the electric circuit which may be of short duration or upon a predetermined low overload existing for an extended interval of time, fusion takes place promptly in the area of the thin sheet conductor about the point to provide an ever widening gap between the conductors.

5. An electric plug fuse comprising a hollow plug member having an external metal screw shell and a metal contact rivet forming electrical connections for an electric circuit and a transparent window, a thin sheet conductor of fuse metal in the plug member adjacent the transparent window and electrically connected to the metal screw shell, a rod shaped conductor having fuse metal of lower melting point than that of the thin sheet conductor in the plug member and electrically connected to the metal contact rivet and having its end engaging the under side of the thin sheet conductor at a point

within the area of the thin sheet conductor, the arrangement being such that, upon a predetermined high overload in the electric circuit or upon a predetermined low overload existing for an extended interval of time, fusion takes place in the area of the thin sheet conductor about the point to provide an ever widening gap between the conductors.

6. An electric cartridge fuse comprising a hollow tube member having a metal fuse cap at each end forming electrical connections for an electric circuit, a thin sheet conductor of fuse metal in the tube member electrically connected to one of the metal fuse caps, a rod shaped conductor having fuse metal of lower melting point than that of the thin sheet conductor in the tube member and electrically connected to the other metal fuse cap and having its end engaging one side of the thin sheet conductor at a point within the area of the thin sheet conductor, the arrangement being such that, upon a predetermined high overload in the electric circuit or upon a predetermined low overload existing for an extended interval of time, fusion takes place in the area of the thin sheet conductor about the point to provide an ever widening gap between the conductors.

7. An electric fuse comprising a thin sheet conductor of fuse metal having a substantial planar dimension and a thickness sufficient to be self-supporting, a rod-shaped conductor arranged normal to the thin sheet conductor and having its end physically and electrically conductively secured to one side of the thin sheet conductor at a point within the planar area thereof, the transverse dimensions of the securing point between the conductors being greater than the thickness of the thin sheet conductor and the cross-sectional conductive area of the thin sheet conductor immediately about the securing point being less than any other cross-sectional conductive area of the thin sheet conductor, and means for connecting the conductors in series in an electric circuit so that, upon a predetermined overload in the electric circuit, fusion takes place in the area of the thin sheet conductor about the securing point to provide an ever-widening gap between the conductors.

8. An electric fuse comprising a thin sheet conductor of fuse metal having a substantial planar dimension and a thickness sufficient to be self-supporting, a rod-shaped conductor arranged normal to the thin sheet conductor and having its end physically and electrically conductively secured to one side of the thin sheet conductor at a point within the planar area thereof, the transverse dimensions of the securing point between the conductors being greater than the thickness of the thin sheet conductor and the cross-sectional conductive area of the thin sheet conductor immediately about the securing point being less than any other cross-sectional conductive area of the thin sheet conductor, a receptacle having external electrical connections, and means for mounting the conductors in the receptacle and connecting the same in series with the electrical connections and hence in series in an electric circuit so that, upon a predetermined overload in the electric circuit, fusion takes place in the area of the thin sheet conductor about the securing point to provide an ever-widening gap between the conductors.

9. An electric fuse comprising a thin sheet conductor of fuse metal having a substantial planar dimension and a thickness sufficient to be self-supporting, a rod-shaped conductor arranged normal to the thin sheet conductor and having its end physically and electrically conductively secured to one side of the thin sheet conductor at a point within the planar area thereof, the transverse dimensions of the securing point between the conductors being greater than the thickness of the thin sheet conductor and the cross-sectional conductive area of the thin sheet conductor immediately about the securing point being less than any other cross-sectional conductive area of the thin sheet conductor, indicia on the opposite side of the thin sheet conductor adjacent the securing point

between the conductors for indicating the condition of the electric fuse, a receptacle having external electrical connections and a transparent window, and means for mounting the conductors in the receptacle with the indicia visible through the transparent window and with the conductors in series with the electrical connections and hence in series in an electric circuit so that, upon a predetermined overload in the electric circuit, fusion takes place in the area of the thin sheet conductor about the securing point, to provide an ever-widening gap between the conductors, and for obliterating the indicia.

10. An electric plug fuse comprising a hollow plug member having an external screw shell and a metal contact rivet forming electrical connections for an electric circuit and a transparent window, a thin sheet conductor of fuse metal in the plug member adjacent and parallel to the transparent window and electrically connected to the metal screw shell and having a substantial planar dimension and a thickness sufficient to be self-supporting, a rod-shaped conductor in the plug member electrically connected to the metal contact rivet and arranged normal to the thin sheet conductor and having its end physically and electrically conductively secured to the under side of the thin sheet conductor at a point within the planar area thereof, the transverse dimensions of the securing point between the conductors being greater than the thickness of the thin sheet conductor and the cross-sectional conductive area of the thin sheet conductor immediately about the securing point being less than any other cross-sectional conductive area of the thin sheet conductor, said conductors being connected in series through said screw shell and contact rivet so that, upon a predetermined overload in the electric circuit, fusion takes place in the area of the thin sheet conductor about the securing point, to provide an ever-widening gap between the conductors.

11. An electric plug fuse comprising a hollow plug member having an external screw shell and a metal contact rivet forming electrical connections for an electric circuit and a transparent window, a thin sheet conductor of fuse metal in the plug member adjacent and parallel to the transparent window and electrically connected to the metal screw shell and having a substantial planar dimension and a thickness sufficient to be self-supporting, a rod-shaped conductor in the plug member electrically connected to the metal contact rivet and arranged normal to the thin sheet conductor and having its end physically and electrically conductively secured to the under side of the thin sheet conductor at a point within the planar area thereof, indicia on the upper side of the thin sheet conductor adjacent the securing point between the conductors and visible through the transparent window for indicating the condition of the electric fuse, the transverse dimensions of the securing point between the conductors being greater than the thickness of the thin sheet conductor and the cross-sectional conductive area of the thin sheet conductor immediately about the securing point being less than any other cross-sectional conductive area of the thin sheet conductor, said conductors being connected in series through said screw shell and contact rivet so that, upon a predetermined overload in the electric circuit, fusion takes place in the area of the thin sheet conductor about the securing point, to provide an ever-widening gap between the conductors and for obliterating the indicia.

12. An electric cartridge fuse comprising a hollow tube member having a metal fuse cap at each end forming electrical connections for an electric circuit, a thin sheet conductor of fuse metal in the tube member electrically connected to one of the metal fuse caps and having a substantial planar dimension and a thickness sufficient to be self supporting, a rod-shaped conductor in the tube member electrically connected to the other fuse cap and arranged normal to the thin sheet conductor and having

its end physically and electrically conductively secured to one side of the thin sheet conductor at a point within the planar area thereof, the transverse dimensions of the securing point between the conductors being greater than the thickness of the thin sheet conductor and the cross-sectional conductive area of the thin sheet conductor immediately about the securing point being less than any other cross-sectional conductive area of the thin sheet conductor, said conductors being connected in series through said fuse caps so that, upon a predetermined overload in the electric circuit, fusion takes place in the area of the thin sheet conductor about the securing point to provide an ever-widening gap between the conductors.

13. An electric fuse comprising a thin sheet conductor of fuse metal having a substantial planar dimension and a thickness sufficient to be self-supporting, a rod-shaped conductor arranged normal to the thin sheet conductor and having fuse metal of lower melting point than that of the thin sheet conductor and having its end physically and electrically conductively secured to one side of the thin sheet conductor at a point within the planar area thereof, the transverse dimensions of the securing point between the conductors being greater than the thickness of the thin sheet conductor and the cross-sectional conductive area of the thin sheet conductor immediately about the securing point being less than any other cross-sectional conductive area of the thin sheet conductor, and means for connecting the conductors in series in an electric circuit so that, upon a predetermined high overload in the electric circuit which may be of short duration, or upon a predetermined low overload existing for an extended interval of time, fusion takes place promptly in the area of the thin sheet conductor about the securing point to provide an ever-widening gap between the conductors.

14. An electric fuse comprising a thin sheet conductor of fuse metal having a substantial planar dimension and a thickness sufficient to be self-supporting, a rod-shaped conductor arranged normal to the thin sheet conductor and having a fusible eutectic alloy of lower melting point than that of the thin sheet conductor and having its end physically and electrically conductively secured to one side of the thin sheet conductor at a point within the planar area thereof, the transverse dimensions of the securing point between the conductors being greater than the thickness of the thin sheet conductor and the cross-sectional conductive area of the thin sheet conductor immediately about the securing point being less than any other cross-sectional conductive area of the thin sheet conductor, and means for connecting the conductors in series in an electric circuit so that, upon a predetermined high overload in the electric circuit which may be of short duration, or upon a predetermined low overload existing for an extended interval of time, fusion takes place promptly in the area of the thin sheet conductor about the securing point to provide an ever-widening gap between the conductors.
